US00D458227S

(12) **United States Design Patent** (10) Patent No.: **US D458,227 S**
(45) Date of Patent: **** Jun. 4, 2002**

(54) **PCB CONNECTOR**

(75) Inventor: **Ian Edward Aldridge**, Hampshire (GB)

(73) Assignee: **Contour Electronics Limited** (GB)

(**) Term: **14 Years**

(21) Appl. No.: **29/144,480**

(22) Filed: **Jul. 3, 2001**

(51) LOC (7) Cl. **13-03**

(52) U.S. Cl. **D13/147**

(58) Field of Search **D13/147; 439/660, 439/559, 562, 564, 55, 76.1, 78**

(57) **CLAIM**

The ornamental design for a PCB connector, as shown and described.

DESCRIPTION

FIG. 1 is a top plan view of a PCB connector showing my new design;

FIG. 2 is a front view thereof;

FIG. 3 is a cross-sectional view from 3 to 3 in FIG. 2;

FIG. 4 is a view from one side; and,

FIG. 5 is a view from the other side.

1 Claim, 1 Drawing Sheet

FIG. 1

FIG. 4

FIG. 2

FIG. 5

FIG. 3
